UNITED STATES PATENT OFFICE.

PHILIP DIEHL, OF ELIZABETH, NEW JERSEY, ASSIGNOR TO THE SINGER
MANUFACTURING COMPANY, OF NEW JERSEY.

TREADLE MECHANISM.

SPECIFICATION forming part of Letters Patent No. 630,194, dated August 1, 1899.

Application filed December 8, 1898. Serial No. 698,609. (No model.)

To all whom it may concern:

Be it known that I, PHILIP DIEHL, a citizen of the United States, residing at Elizabeth, in the county of Union and State of New Jersey, have invented certain new and useful Improvements in Treadle Mechanisms, of which the following is a specification, reference being had therein to the accompanying drawings.

- 10 This invention relates to that class of treadle mechanisms for use in driving sewing-machines, lathes, and the like in which power is transmitted to the driving-wheel shaft from swinging or pendulous treadle-levers through suitable clutches connecting with said shaft, the object of the invention being to provide a treadle mechanism of the class referred to which is simple in construction and light running and practically noiseless in operation.
- 15 To this end the improved treadle mechanism comprises two swinging segment-gears meshing with pinions having clutch connections with a driving-wheel shaft preferably mounted to run on ball-bearings, one of said segment-gears being connected with a treadle-shaft mounted in suitable bearings and provided with a swinging treadle arm or lever and the other of said segment-gears and its treadle arm or lever being mounted to swing 20 on said shaft, all as will be hereinafter more fully described.

In the accompanying drawings, Figure 1 is a front side view of a sewing-machine stand embodying the invention. Fig. 2 is a sectional end view of the same on line 2 2, Fig. 1, with the table removed and with the outline of a side frame in dotted lines. Fig. 3 is a detail sectional view showing the driving-shaft and its ball-bearings and clutch devices. Fig. 4 is an enlarged detail view of one of the ball-boxes, and Fig. 5 a detail view of one of the loose clutch-collars and its clutch-dog.

A denote the legs or side frames of a sewing-machine stand, and B a brace connecting said legs or side frames and suitably bolted thereto, said brace being furnished on its front side with forwardly-projecting lugs b, in which is journaled the rocking treadle-shaft C, provided with a depending treadle 45 arm or lever c, having a pivoted foot-piece c'.

Attached to the right-hand end of the shaft

C is a segment-gear C', and loosely mounted on said shaft by its collar c² is a second segment-gear C², with which is rigidly connected a second treadle arm or lever c³, also having 55 a pivoted foot-piece c'.

D is the driving-wheel shaft, provided with the driving wheel or pulley D', which is to be belted to a sewing-machine or other pulley to be driven. Loosely mounted on the shaft D 60 are two collars d, each provided with a pinion d', with which the segment-gears C' C² mesh, said collars d both having clutch connections, by means of spring-pressed clutch-dogs d², with an interposed hub or collar d³, 65 fixed to the said shaft D, or it may be integral therewith. To reduce friction, wear, and noise, the driving-wheel shaft D is preferably constructed with conical ends running in ball-bearings, one or both of which may be adjustable in any suitable manner to take up 70 wear when necessary.

F is a knee brake-lever having a brake-shoe f, of rubber or other suitable material, adapted to be forced against the side of the 75 driving-wheel D' against the stress of a retracting-spring f'.

In the operation of the improved treadle mechanism the clutch-dogs d² are caused by the action of the spring d⁴ to grip flanges of 80 the fixed hub or collar d³, and thus rotate the shaft D, when the treadle arms or levers c and c³ are swung forward or from the operator, said clutch-dogs being released from said collar d³ when the movements of said treadle 85 arms or levers are reversed, so as to move freely backward with the loose collars d and pinions d' when the movements of said pinions and loose collars are reversed by the segment-gears C' and C², connected with said 90 treadle arms or levers and meshing with said pinions. The segment-gears C' C² are in operation to be swung back and forth alternately by their operating treadle arms or levers c c³, as will be understood.

By employing a short and comparatively light driving-wheel shaft having its bearings in a loop at one side of the brace B, said loop consisting of the bars b' and b² and their upper and lower connections, and by arranging 100 the two swinging segments and their clutch connections with said shaft in said loop, these

parts are located entirely out of the way of the operator, this arrangement of these parts being more compact and convenient than in the constructions of swinging treadle mechanisms heretofore in use, in which long and comparatively heavy driving-wheel shafts have been employed and in which the segment-gears and their clutch connections with the driving-wheel shafts were in front of the operator and were thus more or less in the way.

The ball-bearings for the conical ends of the driving-wheel shaft D which are preferably employed consist, as herein shown, of ball cases or boxes e' e^2 , secured in the bars b' b^2 of the brace B, and which bars form the loop inclosing the driving-wheel shaft. Each of these boxes contains a series of balls e , surrounding a conical end of said shaft, and the said balls being held in their cases or boxes by rings or washers e^3 , held in the ball cases or boxes by slightly-undercut gains formed at the ends of the boxes, and into which gains the washers, originally formed slightly crowning, are pressed. The box e' is secured in the bar b' by a set-screw e^4 , and the box e^2 has screw-threaded parts e^5 fitting in a tapped hole in the bar b^2 to permit of delicate adjustment to take up wear, a set-screw e^6 , engaging said box between its threaded parts, serving to hold said box in any desired position.

Having thus described my invention, I claim and desire to secure by Letters Patent—

1. In a treadle mechanism, the combination, with a stand comprising legs or side frames and a connecting-brace provided at one end with a loop, of a driving-wheel shaft mounted in said loop, a clutch hub or collar rigid with said shaft, collars loose on said shaft and having clutch connections with said fixed hub or collar, said loose collars being provided with pinions, two independently-movable, swinging segment-gears also arranged in said loop and meshing with said pinions, and swinging treadle arms or levers connected with said segment-gears.

2. In a treadle mechanism, the combination with a stand comprising legs or side frames and a connecting-brace provided at one end with a loop, of a driving-wheel shaft mounted in said loop, a fixed clutch hub or collar on said shaft, loose collars having clutch connections with said fixed hub or collar and provided with pinions, said shaft having conical ends, ball-bearings in which the said conical ends of said shaft are mounted, independently-movable segment-gears meshing with said pinions, and swinging treadle arms or levers connected with said segment-gears.

3. In a treadle mechanism, the combination with a rock-shaft mounted in suitable bearings, of a depending treadle arm or lever and a segment-gear both attached to said shaft, a second segment-gear loosely mounted on said

shaft so as to rock thereon, a treadle arm or lever rigidly connected with said loosely-mounted segment-gear, and a driving-wheel shaft with which said segment-gears are operatively connected.

4. In a treadle mechanism, the combination with a rock-shaft mounted in suitable bearings and provided with a depending treadle arm or lever and with a segment-gear, of a second segment-gear loosely mounted on said shaft, so as to rock thereon, and having a rigid treadle arm or lever, a driving-wheel shaft, a single fixed clutch hub or collar and two loose collars all mounted on said shaft, said loose collars having clutch connections with said fixed clutch hub or collar.

5. The combination with the treadle-shaft C mounted in suitable bearings and provided with the treadle arm or lever c and the segment-gear C', of the swinging segment-gear C² having its pivotal bearing on the said shaft, the treadle arm or lever c³ rigidly connected with said segment-gear C², the driving-wheel shaft D, the pulley D', the fixed hub or collar d³ and the loose collars d provided with pinions d' and having clutch connections with said fixed hub or collar d³.

6. The combination with the legs or side frames A, A, the brace B connecting said legs or side frames and provided on its front side with the forwardly-projecting lugs b, and the treadle-shaft C having its bearings in said lugs, the treadle arm or lever c and the segment-gear C', of the swinging segment-gear C² having its pivotal bearing on the said shaft, the treadle arm or lever c³ rigidly connected with said segment-gear C², the driving-wheel shaft D, the pulley D', the fixed hub or collar d³, and the loose collars d provided with pinions d' and having clutch connections with said fixed hub or collar d³.

7. In a treadle mechanism, the combination with a treadle-operated driving-wheel shaft provided with conical end portions, of ball-bearings for said shaft consisting of boxes or cases each having a series of balls encircling a conical end portion of said shaft, and a washer secured at the end of each box in a slightly-undercut gain to hold the balls in the boxes.

8. In a treadle mechanism, the combination with a treadle-operated driving-wheel shaft provided with conical end portions, of ball-bearings for said shaft consisting of boxes or cases each having a series of balls encircling a conical end portion of said shaft, and a washer secured at the end of each box in a slightly-undercut gain to hold the balls in the boxes, one of said boxes having a screw-thread adjustment to take up wear.

In testimony whereof I affix my signature in the presence of two witnesses.

PHILIP DIEHL.
